UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BREASTING MACHINE.

1,384,178.

Specification of Letters Patent. Patented July 12, 1921.

Application filed February 8, 1917. Serial No. 147,478.

To all whom it may concern:

Be it known that I, Louis A. Casgrain, a citizen of the United States, residing at Beverly, in the county of Essex and State 5 of Massachusetts, have invented certain Improvements in Heel-Breasting Machines, of which the following description, in connection with the accompanying drawings, is a specification, like reference characters on 10 the drawings indicating like parts in the several figures.

This invention relates to heel breasting machines and particularly to a machine for breasting heels before they are attached.

15 Heretofore it has been almost invariably the practice in this country to breast heels after they have been attached to shoes, for the reason that in this way the breasting cut can be made in proper relation to the other parts of the shoe, the requirements 20 of style demanding great accuracy and uniformity in the relation of the plane of the breast to the plane of the shank and to the longitudinal median line of the shoe. More 25 recently, however, manufacturing conditions have been such as to create a demand for a machine for breasting unattached heels, particularly low heels such as are used 30 on some men's shoes and on boots and shoes destined for military use. In the manufacture of such footwear the chief considerations are large production with uniformity and durability of product. By breasting 35 heels before they are attached this operation can be performed more expeditiously and all danger of accidental injury to the shoe shank by the breasting knife is obviated.

40 The general object of this invention is to provide an improved machine for this purpose which will operate with accuracy and at a high rate of speed.

45 A feature of this invention consists in the combination with a reciprocating knife, of a gage so arranged that in any position of the knife and gage only a predetermined portion of the heel can be introduced beneath the knife, and in no position of the 50 gage and knife can the heel as a whole be introduced between the gage and knife, in which event the heel or the machine would be damaged or both. As herein shown, the gage is positively moved with the knife in 55 both directions and the vertical space be-

tween the gage and the knife is always less than the height of the heel. Therefore, in any position of the knife such that a heel may be fed under the knife, the gage is in position to arrest the heel in position to 60 have a predetermined portion of the breast end of the heel removed by the knife, and during the cutting operation of the knife the gage is moved out of the way of the chip cut off by the knife to permit it to 65 fall away from the machine.

Another feature of the invention consists 70 in the combination with heel breasting means, of a heel clamp, and means for moving the breasting means and clamp constructed and arranged to cause the clamp to release the heel by the time that the breasting means begins its return movement, so that the operator may remove the heel 75 as soon as possible after the breasting operation is complete. Furthermore, the movements of the breasting means and the clamp are so related that the clamp will be moved to permit a heel to be presented to the knife 80 as soon as the breasting means begins to move away from the heel when no heel is in the machine, and further the heel is clamped at an early point in the movement of approach of the knife to the heel so that 85 the operator may safely let go of that heel and seize another for insertion in the machine as soon as the breasting operation is completed. As herein shown, the knife carrier has a frictional connection with the 90 clamping means so that the clamping means is moved yieldingly with the knife, and stops are arranged to limit movement of the clamping means to cause the desired movement of the knife and clamping means relatively or together to effect the functions 95 above set forth. Furthermore, it will be noted that by reason of this frictional connection, the pressure of the clamp upon the heel will be constant throughout the period 100 of contact of the clamp with the heel.

These and other features of the invention will appear more fully from the following detailed description when read in connection with the accompanying drawings and 105 will be pointed out in the appended claims.

In the drawings,

Figure 1 is a side view of the upper portion of a heel breasting machine embodying this invention; and

Fig. 2 is a front view of the machine.

Referring to the drawings, the frame of the machine is indicated by the numeral 2. In the upper part of the frame 2 a slide 4 is mounted for vertical reciprocation. The slide 4 is connected by a rod 8 to a crank (not shown) on a shaft mounted in the lower part of the machine frame. The connection between the shaft and the driving wheel of the machine preferably includes a repeating one revolution clutch, that is, a clutch which keeps the machine in operation while its operating treadle is held depressed and which will stop the machine at the end of the cycle when the treadle is released. Of course, if the treadle is depressed and immediately released, the machine would stop at the end of one revolution. In order to keep the machine in continuous operation while permitting the operator to remove his foot from the treadle, a treadle latch may be provided which holds the treadle depressed until released by operation of a trip arranged adjacent to the treadle.

The slide 4 has a lateral projection 19 carrying a knife 20 which is moved thereby toward and from a table 22 upon which is clamped by a screw 24 a cutting block 26. The table 22 is mounted on a support 28 by trunnions 30, the axes of which lie under the knife edge and about which the table and block are adjustable for varying the angular relation of the heel and the knife. A screw 32 threaded into the table 22 and lying in a slot 33 formed in the support 28 serves to hold the parts in adjusted position. The support 28 is fixed to the upper end of a vertically adjustable post 34 which is pivoted on the machine frame near the floor for adjustment perpendicularly to the plane of the knife. An arm 36 and a bracket 38 carry, respectively, screws 40, 42 arranged to engage opposite sides of the machine frame. By these screws the position of the support 28 relatively to the knife may be varied and hence the axis of the trunnions 30 can be properly positioned relatively to the knife edge in a direction perpendicular to the plane of the knife.

The heels to be breasted are placed one at a time upon the cutting block 26, preferably with the tread face of the heel in contact with the block. The lateral position of the heel is preferably determined by a single side gage 50 held by a split clamp 52 and adjustable laterally of the cutting block by a thumb head 54 having a stem mounted for rotation in the split clamp 52 and having threaded engagement with the gage 50.

To position the front face or breast of the heel at the proper angle relatively to the knife and to determine the amount to be cut off by the knife, a gage 60 is provided.

The gage 60 is connected to a support 62 by means of a T-guide 61 (Fig. 2) engaging a T-slot 63 in the support 62 which is adjustably mounted on the lower ends of side rods 64, the upper ends of which are fixed to the knife carrier 19. The gage 60 is adjustable relatively to its support 62 by means of a screw 65 threaded into the support 62 and having a flange 66 engaging a suitable recess in the gage 60. The front face of the gage against which the heel is positioned, instead of being flat, is preferably formed so as to engage the heel only at separated points on the heel breast so that the rough heel breast will be positioned positively and uniformly and rocking of the heel in a horizontal plane will be prevented. As shown (Fig. 2), two ribs 68 are provided at the lateral ends of the gage with which the heel breast contacts near its ends. The rear face 70 of the gage 60 is inclined downwardly and to the rear so that the chip removed from the breast by the knife will readily slide off the inclined face of the gage into a chute or receptacle. It sometimes happens that the chip, instead of falling as a whole upon the inclined face of the gage, breaks in two, leaving a portion, generally the cut off part of the lower lift, resting on the portion of the block which extends beyond the knife. To prevent this chip fragment from interfering with the positioning of the next heel against the gage, a space 69 is provided below the front face of the gage and the ribs 68 into which the fragment may be pushed by a succeeding heel.

It is important that the heel be held firmly against the cutting block during the action of the knife to overcome any tendency of the knife to displace the heel, and it is also highly important that the heel be released by its holding means as early as possible after the heel is breasted to allow the operator time to remove the breasted heel and insert an unbreasted heel. To hold the heel, a clamping member 76 is provided which consists (as shown) of a plate bent at right angles having one portion disposed to present an edge face to the heel in the direction of the knife edge and adjacent to it and having the other portion secured to a bar 78. The bar 78 is guided through a neck 39 of the bracket 38 and at its upper end, which is preferably rectangular in cross section, slides in friction clamping means attached to the knife carrying slide. The clamping means comprises rigid portions 75, 77 held together by screw bolts 85. Between these portions are arranged friction plates 80, 82 of vulcanized fiber or other suitable material, one on each side of the bar. The plate 82 has a backing plate 84 which is forced toward the bar to produce the required amount of friction by a spring 86, the tension of

which may be carried by a screw plug 88. The amount of movement of the clamp bar 78 is limited and adjusted by means of clamp collars 90, 92 on the bar, one above and one 5 below the neck 39 of the bracket 38.

The collar 90 is, of course, adjusted so that the clamping member 76 contacts with the heel before the collar contacts with the neck 39. This collar prevents excess movement 10 of the clamping member when no heel is in the machine and, since the clamping member is not allowed to move far below clamping position, it is raised more quickly when the knife starts upwardly and permits 15 the operator, therefore, to insert the first heel earlier in the cycle of the machine. In subsequent cycles the breasted heel will be released as soon as the upward movement of the knife begins, giving the operator as 20 much time as possible to remove the breasted heel and insert an unbrested one before the knife again descends. The clamping member is prevented by the clamp collar 92 from ascending as high as the knife, and 25 hence when the knife descends the heel is clamped before the knife reaches it.

In the operation of the machine, supposing the machine to be at rest, a heel is placed on the block 26 with the tread face down. 30 The heel is then slid along the block beneath the knife, being positioned at the side by the gage 50 and at the breast by engagement with the two ribs 68 of the breast gage which touch the end portions of the breast. The 35 clutch of the machine is tripped and the clamping member 76 descends by reason of the friction of the plates 80, 82 upon the bar 79 carrying the clamping member 76 which engages the heel and clamps it firmly against 40 the cutting block before the knife reaches it. The plates 80, 82 sliding on the bar 79 maintain a constant and continuous pressure upon the heel, and the knife descending relatively to the clamping member breasts the heel and 45 carries with it the gage 60 out of the way of the chip being removed. When the knife has reached the cutting block the gage is in the dotted line position of Fig. 1 and the chip separated from the heel by the knife 50 falls upon the inclined face of the gage and is directed away from the machine. When the knife starts to ascend the friction between the plates 80, 82 and the bar 79 causes the clamping member to be lifted immediately from the heel, whereupon the operator removes it and immediately puts another heel in its place. While the next heel is being pushed in the knife and gage are ascending, but since the space between the 55 knife and the gage is less than the thickness of a heel the heel cannot be forced into the space between them but must engage either the knife or the gage. If the heel engages the knife no harm is done and continued 60 inward pressure will cause it to contact with

the gage when the gage has reached its upper position. At this time, any chip or fragments which may have caught on the portion of the block 26 which projects beyond the knife are pushed by the heel which is 70 being inserted into the space below the gaging face of the gage and do not interfere with the proper positioning of the heel against the gage.

When the heel is being breasted with its 75 tread face against the cutting block the angle between the breast and tread faces of the heel may be varied by loosening the screw 32 and raising the outer end of the block 26 about the center 30 out of horizontal position, then setting up the screw 32. 80

When the heels are to be breasted with the tread face uppermost the outer end of the block will be adjusted downwardly out of the horizontal to give the proper inclination to the heel breast. The operation of the machine will then be substantially as 85 above described.

Having fully described my invention, what I claim as new and desire to secure by United 90 States Letters Patent is:—

1. In a machine for breasting unattached heels, the combination of a vertically reciprocating knife, a cutting block, a gage arranged for vertical movement across one 95 end of the block into a position where its top is above the heel when the heel is fed and for movement out of gaging position relatively to a heel on the block when the breasting is completed, and means for operating the gage to maintain the vertical distance between the top of the gage and the knife edge constantly less than the height of a normal heel.

2. In a machine of the class described, the 105 combination of a knife carrier, a knife in the carrier, a gage carrier, a cutting block, connections between the gage carrier and the knife carrier to effect movements of the gage carrier past the end of the block equal 110 to the movements of the knife and in the same direction, and a gage on the carrier arranged to position a heel on the block for the action of the knife.

3. A machine of the class described having, in combination, a cutting block, a knife holder, a knife in the holder, a gage carrier, a breast gage carried thereby, means for maintaining a fixed relation between the knife holder and the gage carrier to maintain unchanged the relative position of the knife and the gage in the direction of the cut of the knife, and means for relatively moving the cutting block and the knife holder to effect the cutting operation.

4. In a machine for breasting unattached heels, the combination of a knife holder, a cutting block, a gage arranged at the end of the block with its top above the heel when the heel is fed and having a fixed relation 130

4
relatively to the knife, and means for relatively moving the knife and block in the plane of the knife to cause the heel to be breasted and the gage and block to be moved
5 relatively to allow the chip to fall off of the cutting block.

6. In a machine of the class described, the combination of a knife carrier, a knife in the carrier, a gage carrier, substantially
10 rigid rods fixedly connecting the gage carrier to the knife carrier, and a gage on the carrier coextensive with the heel breast and arranged for right line adjustment bodily toward and from the heel to vary the amount
15 of material cut off by the knife in its cutting operation.

7. In a machine for breasting heels, the combination of breasting means movable toward and from the heel, a heel clamping
20 member movable toward and from the heel and movable relatively to the knife in timed relation thereto, and means constructed and arranged to cause the clamping member to release the clamped heel by the time
25 that the breasting means begins its return movement.

8. In a machine for breasting unattached heels, the combination of a cutting block, a knife carrier arranged to reciprocate toward
30 and from the block, a heel clamping member movable toward and from the block, and connections between the knife and the clamping member constructed and arranged to cause the clamp to clamp the heel throughout the cutting action of the knife and to release the heel as soon as the knife begins to return after its breasting stroke.

9. In a machine for breasting heels, the combination of breasting means movable toward and from the heel, heel clamping means movable to and from the heel, and means for moving the breasting means and the clamping means at times together and at times relatively, the movement together
40 taking place at the beginning of each upward movement of the breasting means whether or not a heel is in the machine.

10. In a machine for breasting heels, the combination of a cutting block, breasting means movable toward and from the cutting block, clamping means movable toward and from the block, connections between the breasting means and the clamping means whereby they move at times together and at times relatively, and means for limiting the movement of the clamping means in such manner that the clamping means is moved to admit a heel upon the block immediately after the breasting means begins to move
50 away from the block when no heel is in the machine.

11. In a machine for breasting unattached heels, a cutting block, a knife carrier arranged to reciprocate toward and from the upper face of the block, heel clamping means

movable toward and from a heel on the block, and connections between the clamping member and the knife carrier whereby they may move together, the parts being constructed and arranged to clamp the heel by 70 the time that the knife begins its cutting action and to release it as soon as the knife begins its return movement.

12. In a machine of the class described, a work support, a reciprocating knife, a 75 clamping member arranged to engage a heel to hold the heel on the support during the action of the knife, and friction means for moving the clamping member toward and from the support as the knife is reciprocated.

13. In a machine for breasting unattached heels, a cutting block, a knife carrier arranged to reciprocate toward and from one face of the block, clamping means comprising a bar arranged to be reciprocated in the same direction as the knife carrier toward and from a heel on the block, and a sliding connection between the bar and the carrier whereby they are frictionally held for movement together and the bar is actuated from the carrier to clamp a heel when the carrier descends and to unclamp the heel when the carrier ascends.

14. In a machine for breasting unattached heels, a cutting block, a knife carrier arranged to reciprocate toward and from the upper face of the block, heel clamping means comprising a bar arranged to be reciprocated in the same direction as the knife carrier toward and from a heel on the block, a sliding connection between the bar and the carrier whereby they are frictionally held for movement together, and means for limiting the movement of the clamping bar 105 relatively to the movement of the knife.

15. In a machine for breasting unattached heels, a cutting block, a knife carrier arranged to reciprocate toward and from one face of the block, a heel clamping member 110 movable toward and from a heel positioned on the block, and means operated by movement of the knife for maintaining the clamping member against the heel with a constant pressure throughout the breasting 115 operation.

16. In a machine of the class described, the combination of a reciprocating knife, a cutting block against which the knife acts, a support for the cutting block pivoted on 120 an axis extending parallel with the knife edge, said support being movable substantially perpendicularly to the knife edge, and means for adjusting the support to locate said pivot in the plane of action of the knife 125 and to maintain it in adjusted position.

In testimony whereof I have signed my name to this specification.

LOUIS A. CASGRAIN.
